UNITED STATES PATENT OFFICE.

EDWARD F. McCARTHY, OF CHICAGO, ILLINOIS, ASSIGNOR TO VACUUM MACHINERY CO., OF MARINETTE, WISCONSIN, A CORPORATION OF WISCONSIN.

HYDROTURBINE VACUUM-PUMP.

1,296,828.

Specification of Letters Patent. Patented Mar. 11, 1919.

Application filed January 28, 1918. Serial No. 214,079.

To all whom it may concern:

Be it known that I, EDWARD F. McCARTHY, a citizen of the United States, residing at Chicago, in the county of Cook and 5 State of Illinois, have invented certain new and useful Improvements in Hydroturbine Vacuum-Pumps, of which the following is a specification.

This invention relates to improvements in 10 hydroturbine vacuum pumps and one of the objects of the same is to provide an improved submerged pump of this character provided with pockets or chambers therein, the liquid alternately filling and being discharged 15 from the chambers or pockets, thereby causing a suction or partial vacuum in a suction tube, and the pump being submerged the benefit of a water seal will be obtained.

20 To the attainment of these ends and the accomplishment of other new and useful objects as will appear, the invention consists in the features of novelty in substantially the construction, combination and arrangement 25 of the several parts hereinafter more fully described and claimed and shown in the accompanying drawings, illustrating this invention and in which:

Figure 1 is a vertical longitudinal sectional view of an improved apparatus of 30 this character, constructed in accordance with the principles of this invention.

Fig. 2 is a horizontal sectional view as taken on line 2—2, Fig. 1.

Fig. 3 is a horizontal sectional view taken 35 on line 3—3, Fig. 1.

Fig. 4 is a horizontal sectional view taken on line 4—4, Fig. 1, looking in the direction of the arrows.

Fig. 5 is a horizontal sectional view taken 40 on line 5—5, Fig. 1, looking in the direction of the arrows.

Fig. 6 is a top plan view, partly in section of a modified form of the invention.

Fig. 7 is a side elevation of Fig. 6.

Fig. 8 is a horizontal sectional view taken 45 on line 8—8, Fig. 9, of a modified form of the invention.

Fig. 9 is a vertical sectional view of the 50 form of the invention shown in Fig. 8.

Fig. 10 is a horizontal sectional view taken on line 10—10, Fig. 11, of a modified form of the invention.

Fig. 11 is a vertical sectional view of the 55 form of the invention shown in Fig. 10.

Referring more particularly to the drawings, the numeral 15 designates a receptacle which is partially filled with liquid, the receptacle being provided with an overflow outlet 16, and an outlet 17 for the escape of 60 air and vapor.

Rotatably submerged in the liquid within the receptacle is an element 18, having a top 19 and a bottom 20 spaced from each other and provided between the top and bottom of 65 this element are a plurality of radially disposed ribs or partitions 21, which are closed at their inner ends and are open at their outer ends adjacent the periphery of the element. This element 18 may be constructed 70 in any desired or suitable manner, either by being formed as an integral structure or by being constructed in sections secured together. The element 18 is rotatably supported by means of a shaft 22 which extends 75 through the top 23 of the casing and has secured to it a collar 24, between which collar and the top of the casing is arranged a bearing 25 and by means of which bearing 80 the element 18 is supported. The shaft and 85 the element are rotated in any desired or suitable manner, such as by means of a pulley 26, secured to one end of the shaft 22. The element 18 is supported above the bottom 27 of the casing by means of a suitable bearing 28 into which a depending stem 29 connected with the element projects and packing material 30 may be provided to form a fluid tight joint. If desired a 90 bracket 31, having a bearing 32 may be provided to receive the extremity of the depending stem 29.

A clean-out opening 33 may be provided in the bottom of the receptacle and the receptacle may be supported by means of suitable 95 legs or supports 34.

Arranged adjacent the periphery of the rotary element 18 are a series of standards or baffle members 35 which are preferably of a height to extend above the top of the 100 element 18 and are of a width slightly greater than the width of the opening of the pockets at the periphery of the element. These standards or baffles 35 are preferably provided with a curved inner face 36 which 105 stands in close proximity to the periphery of the element so as to form a closure for the pockets as they pass the standards or baffles to trap or confine the liquid within the pocket. The periphery of the element 110

18, it is of course to be understood, is arranged as closely as possible to the face 36 of the standards or baffles to effectively confine the water within the pockets as the 5 pockets pass the standards or baffles. The top 19 of the element 18 is provided with a plurality of openings 37 therethrough which communicate with the pockets to form an entrance opening for the liquid in the 10 respective pockets. Supported by the standards or baffles 35 is a member 38, preferably in the form of a plate having ears 39 projecting radially therefrom and which ears are adapted to rest upon the uprights 15 or baffles 35 to be secured thereto by means of fastening devices 40 to support the member and to hold it against rotation. Openings 41 are provided in the member 38 which are of a size substantially equal to the openings 20 37 in the top of the rotary element and these openings 41 are spaced from each other in such a manner that the alternate openings 37 in the rotary element 18 will register therewith while the remaining alternate openings 37 in the element 18 will be 25 closed by the space or solid portion of the element 38 between adjacent openings 41.

The bottom face of the member 38 is recessed or cored out as at 42, preferably adjacent the diametric center thereof, and this recessed portion preferably projects into the space between adjacent openings 41, as at 43, so that when the element 18 is rotated, the openings 37 therein which do 30 not register with the openings 41 in the member 38 will be brought into communication with the extended portion 43 of the recess 42, so that these extended portions 43 overlap for a short distance the inner 35 ends of the alternate openings 37. Communicating with the chamber formed by the recessed or cored portion 42 is a pipe 44, in which it is desired to create a suction. 40

With this improved construction, the 45 operation is as follows: It being of course understood that all of the parts are arranged as closely as possible so as to form tight joints, yet permitting the parts to rotate with respect to each other without undue friction.

When the parts are at rest, the element 18, together with the member 38 and the uprights or baffles 35 being submerged, the pockets formed between the radial partitions 50 21 in the element 18 will be filled with the liquid. As soon as the element 18 is rotated, centrifugal force will tend to throw or expel the liquid from the pockets in the element 18 which are open, that is the 55 60 pockets which are not closed by the standards or baffles 35. As the liquid is expelled from the pockets a partial vacuum or suction will be created in the pocket and inasmuch as the liquid is being expelled from the 65 pocket at the time when the pocket is in

communication with the recessed or chambered portion 42 of the member 38, through the medium of the extension 43 thereof, this suction or partial vacuum will be manifested in the pipe 44 thereby creating a suction in 70 that pipe. When the pocket passes out of communication with the chambered or cored portion 42 of the member 38, it will move into registration with one of the openings 41 in the member 38, that is, the inlet opening 37 of the pocket will register with the opening 41, thereby permitting the liquid in the receptacle 15 to enter the pocket in the member 18 by gravity. When the openings 37, 41 are in registration, the open end 75 of the pocket at the periphery of the element will be in the position shown in Fig. 3 with respect to the uprights or baffles 35, that is, they will be closed thereby so that the liquid will be trapped or confined for 80 a short period of time within the pocket, and when the pocket is moved to a position that it will be again opened, the liquid in the pocket will be expelled by the centrifugal force to produce the suction. This 85 operation is continued as long as the element 18 is rotated, with the result that certain of the pockets will be filled with the liquid, while the liquid is being expelled from the other pockets thereby alternately filling and 90 discharging the pockets as they move into and out of registration with the extension 43 of the cored portion 42 of the member 38.

As the liquid in the receptacle 15 rises, it will overflow through the opening 16 and 100 any air or vapor which is formed within the receptacle will pass through the outlet opening 17.

In order to facilitate the operation of this mechanism by forcing the liquid into 105 the pockets when they are aligned with the openings 41 in the member 38, thereby expelling the air more rapidly from the pockets, any suitable means may be provided for catching the liquid as it is expelled from the pocket and utilizing this force to direct the liquid into another of the pockets. To that end there may be provided a pipe or tubular member 45, one adjacent each of the standards or 110 baffles 35, and having an inlet opening 46 adjacent the standard or baffle at that point where the liquid commences to be expelled from the pocket when the pocket moves away from the standard or upright. This 115 tubular member 45 may be shaped to extend over the top of the member 38 and is provided with a discharge outlet 47 which registers with a portion of the openings 41 in the member 38. Thus it will be manifest 120 that as the pocket is advancing toward the standard or baffle 35, the liquid which is being expelled from one pocket will be caught by the tubular member 45 and conveyed into another pocket through the 125 130

opening 41 and just as that pocket is about to be closed by another of the standards or baffles 35.

In the form of the invention shown in Figs. 8 to 11, the rotary element 48 which corresponds with the element 18 is provided with a chamber 49 at its diametric center, and which chamber may be of any desired diameter. The element 48 is provided with a plurality of radially disposed openings or passages 50 extending from the chamber 49 through the periphery thereof and arranged within this chamber 49 is an element 51, having a passage 52 therethrough adapted to be brought into registration with the diametrically opposite passages 50 in the element 48. This element 51 is of a length in one direction substantially equal to the diameter of the chamber 49 and is of a width in another direction somewhat less than the diameter of the chamber and projecting laterally from the sides of the member 51 are flanges 53 to form a passage-way opening vertically through the chamber 49 so that when the chamber 52 in the element 51 is in registration with the diametrically opposite passages 50, the space between the flanges 53 of the member 51 will serve as a means for permitting the liquid to enter by gravity into the other passages 50 to receive the supply of liquid and which supply will be expelled or thrown out of the chambers or passages 50 at the time they are in registration with the opening 52 in the element 51, thereby creating a suction in the chamber 52 which suction manifests itself in a pipe or passage 54, having communication with the chamber 52 through the bottom thereof and which pipe or passage 54 communicates with a pipe 55 leading into the receptacle 15 from the outside of the receptacle. The member 51 is stationary, while the element 48 is rotatable about the member 51. This rotation may be accomplished in any suitable manner, such as by means of a bracket 56 secured to the shaft 57, which corresponds to the shaft 22, shown in the form in Fig. 1, and a bearing 58 may be secured to the bottom of the element 48 so as to encompass the pipe or tubular member 54. Thus it will be seen that the pockets or passages 50 will be alternately filled and discharged of liquid to create a partial vacuum or suction in the pipe 55, when the passage 52 of the member 51 is in registration with the pockets or passages 50.

In the form of the invention shown in Figs. 10 and 11 in addition to the features already described with respect to the form shown in Figs. 8 and 9, uprights or baffles 59, similar to the uprights or baffles 35, may be provided so as to alternately close the pockets or passages 50 during the interval of time that the outlet openings of these

pocket or passages, at the periphery of the element 48 pass across the baffles or standards so as to confine the liquid within the respective pockets or passages 50 and so that the liquid will be expelled with greater centrifugal force from the pocket when the end of the pocket passes away from the adjacent face of the standard or baffle 59.

With this improved construction, it will be manifest that a very powerful suction pump will be produced and being submerged, a partial vacuum will be produced by alternately filling certain of the pockets or chambers with liquid at a predetermined point or certain cycle of revolution of the rotary element and then discharging or expelling the liquid at another predetermined point or cycle of revolution of the rotary element and which partial vacuum or suction is manifested in a suction pipe with which the element has communication.

While the preferred forms of the invention have been herein shown and described, it is to be understood that various changes in the details of construction and in the combination and arrangement of the several parts may be made without departing from the spirit of this invention.

What is claimed as new is:

1. A device of the character described embodying a submerged rotary element having a water chamber therein provided with a discharge outlet, means for rotating said element, means whereby the chamber will be opened to the entrance of fluid at a predetermined point in the rotation of the element, said means operating to close the chamber to the entrance of fluid at another predetermined point in the rotation of the element and while the fluid is being discharged through the outlet, a conduit, and provisions whereby the discharge of the fluid from the said chamber will create a suction in the said conduit.

2. A device of the character described embodying a submerged rotary element having a water chamber therein, means for rotating said element, means whereby the chamber will be alternately filled with the liquid and the liquid discharged therefrom at predetermined points in the rotation of said element, and means whereby a partial vacuum will be produced through said chamber by the discharging action of the liquid therefrom.

3. A device of the character described embodying a submerged rotary element having a water chamber therein, means for rotating said element, means whereby the chamber will be alternately filled with the liquid and the liquid discharged therefrom at predetermined points in the rotation of said element, the said means embodying provisions for arresting the entrance of the liquid into the said chamber, and means whereby a partial vacuum will be produced through said

chamber by the discharging action of the liquid therefrom.

4. A device of the character described embodying a submerged rotary element having a chamber therein provided with a liquid inlet and a discharge outlet, means for opening and closing the chamber to the entrance of liquid at predetermined points in the rotation of the element, the said liquid being discharged from the chamber by centrifugal force at a predetermined point in the rotation of the element and when the chamber is closed to the entrance of liquid thereinto, and means whereby a suction will be created through the chamber by the discharge of the liquid therefrom.

5. A device of the character described embodying a submerged rotary element having a chamber therein provided with a liquid inlet and a discharge outlet, means for opening and closing the chamber to the entrance of liquid at predetermined points in the rotation of the element, the said liquid being discharged from the chamber by centrifugal force at a predetermined point in the rotation of the element and when the chamber is closed to the entrance of liquid thereinto, and a fluid conduit with which the said chamber is adapted to establish communication at a predetermined point in the rotation of the element whereby the discharge of the liquid from the chamber will create a suction in the said conduit.

6. A device of the character described embodying a rotary element having a plurality of liquid chambers therein, means for rotating said element, means for alternately filling certain of said chambers with liquid and expelling the liquid therefrom at predetermined points in the rotation of said element, and means whereby the said operations will produce a partial vacuum.

7. A device of the character described embodying a rotary element having a plurality of liquid chambers therein, means for rotating said element, means for alternately filling certain of said chambers with liquid and expelling the liquid therefrom at predetermined points in the rotation of said element, the said means embodying provisions for trapping and confining the liquid in the chambers during a predetermined portion of the rotation of said element, and means whereby the said operations will produce a partial vacuum.

8. A device of the character described embodying a submerged rotary element having a liquid chamber therein provided with a liquid inlet and a discharge outlet, a fluid inlet chamber closed to the entrance of the submerging liquid, means for rotating said element, and means for alternately filling said liquid chamber and discharging the liquid therefrom, said liquid chamber being

adapted to establish communication with the said fluid chamber during the time that the liquid is being expelled from the liquid chamber whereby such expelling action of the liquid will produce a partial vacuum in the said fluid chamber.

9. A device of the character described embodying a submerged rotary element having a liquid chamber therein provided with a liquid inlet and a discharge outlet, a fluid inlet chamber closed to the entrance of the submerging liquid, means for rotating said element, and means for alternately filling said liquid chamber and discharging the liquid therefrom, said liquid chamber being adapted to establish communication with the said fluid chamber during the time that the liquid is being expelled from the liquid chamber whereby such expelling action of the liquid will produce a partial vacuum in the said fluid chamber, the last recited means embodying provisions for controlling the said discharge outlet during a predetermined portion of the revolution of the said element.

10. A device of the character described embodying a submerged rotary element having a plurality of liquid chambers therein each provided with a liquid inlet and a discharge outlet, a fluid inlet chamber closed to the entrance of the submerging liquid thereinto, means for rotating the said element, and means for alternately filling said liquid chambers and discharging the liquid therefrom, the said filling means embodying provisions for directing the liquid into the chambers under pressure, said liquid chambers being adapted to establish communication with the said fluid chamber during the time that the liquid is being expelled from the liquid chamber whereby such expelling action of the liquid produces a partial vacuum in the said fluid chamber.

11. A device of the character described embodying a submerged rotary element having a plurality of liquid chambers therein each provided with a liquid inlet and a discharge outlet, a fluid inlet chamber closed to the entrance of the submerging liquid thereinto, means for rotating the said element, means for alternately filling said liquid chambers and discharging the liquid therefrom, said liquid chambers being adapted to establish communication with the said fluid chamber during the time that the liquid is being expelled from the liquid chamber whereby such expelling action of the liquid produces a partial vacuum in the said fluid chamber, and means adjacent the path of movement of the discharge outlet of said liquid chambers for directing the expelled liquid into another of the chambers and under pressure.

12. A device of the character described embodying a submerged rotary element having

- ing a plurality of liquid chambers therein each provided with a liquid inlet and a discharge outlet, a fluid inlet chamber closed to the entrance of the submerging liquid thereinto, means for rotating the said element, means for alternately filling said liquid chambers and discharging the liquid therefrom, said liquid chambers being adapted to establish communication with the said fluid chamber during the time that the liquid is being expelled from the liquid chamber whereby such expelling action of the liquid produces a partial vacuum in the said fluid chamber, and means adjacent the path of movement of the discharge outlet of said liquid chambers for directing the expelled liquid into another of the chambers under pressure and while the latter chamber is also open to the entrance of the submerging liquid and out of communication with the said fluid chamber.
13. A device of the character described embodying a submerged rotary element having a liquid chamber therein provided with a liquid inlet and a discharge outlet, a fluid inlet chamber closed to the entrance of the submerging liquid, means for rotating said element, means for alternately filling said liquid chamber and discharging the liquid therefrom, said liquid chamber being adapted to establish communication with the said fluid chamber during the time that the liquid is being expelled from the liquid chamber whereby such expelling action of the liquid will produce a partial vacuum in the said fluid chamber, and an inclosing tank in which the said element is arranged.
14. A device of the character described embodying a closed tank, an air outlet leading from the tank, a rotary element submerged within the tank, said element having a liquid chamber therein, means for rotating the element, a fluid conduit closed to the entrance of the submerging liquid thereinto, and with which conduit the said chamber is adapted to be alternately brought into and out of communication during the rotation of the element, and means whereby the liquid chamber will be filled with the liquid, the liquid being expelled from the liquid chamber during the time that the latter is in communication with the said fluid conduit, whereby the expelling action of the liquid from its chamber will create a suction in the said fluid chamber.
15. A device of the character described embodying a submerged rotary element having a liquid chamber therein provided with a liquid inlet and a discharge outlet, a fluid inlet chamber closed to the entrance of the submerging liquid, means for rotating the said element, and means for alternately filling said liquid chamber and discharging the liquid therefrom, the last said means embodying provisions for controlling the inlet of the said chamber, said liquid chamber being adapted to establish communication with the said fluid chamber during the time that the liquid is being expelled from the liquid chamber whereby such expelling action of the liquid will produce a partial vacuum in the said fluid chamber.
16. A device of the character described embodying a submerged rotary element having a liquid chamber therein provided with a liquid inlet and a discharge outlet, a fluid inlet chamber closed to the entrance of the submerging liquid, means for rotating said element, and means for alternately filling said liquid chamber and discharging the liquid therefrom, the last recited means embodying provisions for controlling the inlet of the chamber and provisions for closing the discharge outlet of the chamber said liquid chamber being adapted to establish communication with the said fluid chamber during the time that the liquid is being expelled from the liquid chamber whereby such expelling action of the liquid will produce a partial vacuum in the said fluid chamber.
17. A device of the character described embodying a submerged rotary element having a plurality of liquid chambers therein each having a discharge outlet, provisions for filling the chambers with liquid, means for rotating the element whereby the liquid will be expelled by centrifugal force from said chambers at predetermined points in the rotation of the element, means whereby such expelling action of the liquid will create a partial vacuum, and stationary means with respect to which the element is rotatable and operating to close the outlet of the chambers to confine the liquid within the chambers during a portion of the rotation of the said element.
18. A device of the character described embodying a submerged rotary element having a plurality of liquid chambers therein each having a discharge outlet, provisions for filling the chambers with the liquid, means for rotating the element whereby the liquid will be expelled by centrifugal force from said chambers at predetermined points in the rotation of the element, means whereby such expelling action of the liquid will create a partial vacuum, stationary means with respect to which the element is rotatable and operating to close the outlet of the chambers to confine the liquid within the chambers during a portion of the rotation of the said element, and means adjacent the said stationary means adapted to confine the liquid as it is expelled from the chamber and convey the liquid under pressure to another of the chambers.
19. A device of the character described embodying a submerged rotary element hav-

ing a central chamber and a plurality of chambers radiating therefrom and each having a discharge outlet adjacent the periphery of the element, a stationary hollow element in the central chamber and closed to the entrance of the submerging liquid thereto, said stationary element having a passage therethrough for establishing communication between two of the said radiating chambers, a suction pipe connected with the said passage, means for rotating the rotary element to discharge the liquid from the chamber therein by centrifugal force to create a suction in the pipe through the said passage, and provisions for admitting the submerging liquid into other of the chambers while the liquid is being discharged from some of the chambers.

20. A device of the character described embodying a submerged rotary element having a central chamber and a plurality of chambers radiating therefrom and each having a discharge outlet adjacent the periphery of the element, a stationary hollow element in the central chamber and closed to the entrance of the submerging liquid thereto, said stationary element having a passage therethrough for establishing communication between two of the said radiating chambers, a suction pipe connected with the said passage, and means for rotating the rotary element to discharge the liquid from the chamber therein by centrifugal force to create a suction in the pipe through the said passage, a portion of said stationary element being shaped to form entrance openings to some of the said radiating chambers for the

entrance of the submerging liquid while the liquid is being discharged from others of the radiating chambers.

21. A device of the character described embodying a submerged rotary element having a plurality of liquid chambers therein, each having a discharge outlet, provisions for filling the chambers with the liquid, means for rotating the element whereby the liquid will be expelled by centrifugal force from the chambers at predetermined points in the rotation of the element, means whereby such expelling action of the liquid will create a partial vacuum, and means for conveying the liquid under pressure into the chambers.

22. A device of the character described embodying a submerged rotary element having a plurality of liquid chambers therein, each having a discharge outlet, provisions for filling the chambers with the liquid, means for rotating the element whereby the liquid will be expelled by centrifugal force from the chambers at predetermined points in the rotation of the element, means whereby such expelling action of the liquid will create a partial vacuum, stationary means with respect to which the element is rotatable and operating to close the outlet of the chambers to confine the liquid within the chambers during a portion of the rotation of said element, and means for conveying the liquid under pressure into the chambers.

In testimony whereof I have signed my name to this specification on this 24th day of January, A. D. 1918.

EDWARD F. McCARTHY.
